(57) **CLAIM**

The ornamental design for a two arm handwheel, as shown and described.

DESCRIPTION

FIG. 1 is a perspective view of a two arm handwheel of my new invention;

FIG. 2 is a bottom view of FIG. 1, a top view being a mirror image thereof;

FIG. 3 is a front view of FIG. 1; and,

FIG. 4 is a right side view of FIG. 1, a left side view being a mirror image thereof.

The knob and hub portions of the handwheel are shown in broken lines for illustrative purposes only and form no part of the claimed design.
